UNITED STATES PATENT OFFICE.

JOSEPH H. MILLER, OF MOLINE, ILLINOIS.

PILLOW-SHAM HOLDER.

SPECIFICATION forming part of Letters Patent No. 278,581, dated May 29, 1883.

Application filed March 21, 1883. (No model.)

To all whom it may concern:

Be it known that I, J. H. MILLER, of Moline, in the county of Rock Island and State of Illinois, have invented certain new and useful Improvements in Pillow-Sham Holders; and I do hereby declare the following to be a full, clear, and exact description of the invention, such as will enable others skilled in the art to which it pertains to make and use it, reference being had to the accompanying drawings, which form part of this specification.

My invention relates to an improvement in pillow-sham holders; and it consists in a holder which is made from heavy paper, pulp, or any other suitable material, which is made convex upon one side and concave on the other, and adapted to have the sham attached to it in any suitable manner, and then placed over the pillow, as will be more fully described herein-after.

The object of my invention is to produce a support or holder to which the pillow-sham can be attached, and which will support the sham in the desired position while in use.

Figure 1 is a perspective view of my invention. Fig. 2 is a cross-section of the same.

In making my sham-holder I take heavy paper, pasteboard, pulp of any kind, or any other suitable material, and press or mold it into a concavo-convex shape. The thickness

of this holder will be sufficient to make the holder stiff enough to hold the sham in any position that may be desired. The sham will be placed over the convex side of this holder, and either stitched through the holes B at the corners, or fastened in any other suitable manner that may be preferred.

I do not limit myself to any precise shape or manner of constructing the sham-holder, for this may be varied without departing from the spirit of my invention. After the holder is made and the sham attached thereto, as above described, the holder can either be placed directly upon the top of the pillow, or it may be placed at the head of the bed in an inclined position, so as to give the appearance of a pillow, as may be preferred.

Having thus described my invention, I claim—

As a new article of manufacture, a concavo-convex pillow-sham holder made from paper, pulp, or other similar material, and to which the sham is to be attached, substantially as described.

In testimony whereof I affix my signature in presence of two witnesses.

JOSEPH H. MILLER.
